Asahel Goldthwait and Ebenezer Gamsey
Letters Patent

The Schedule referred to in these Letters Patent and making part of the same containing a description in the words of the said Asahel A. Goldthwait and Ebenezer Gamsey themselves of their improvement entitled Goldthwait and Gamsey's Hook for Bits and Harness.

Be it known that we Asahel A. Goldthwait and Ebenezer Gamsey, both of Sharon in the County of Litchfield and State of Connecticut have made an improvement in the useful arts, being a hook or apparatus for fastening the reins to the bits of ... Bridles and fastening together the several parts of harness without the use of buckles, hooks or other fastenings now in use, entitled "Goldthwait and Gamsey's hook for bits and Harness" which is described as follows. The common mode or that sometimes used for fastening the reins to the bits is by means of a hook having a shank or shank with an opening, at one end and a hook at the other, and a spring fastened on the shank passing under the hook consisting of two or more pieces of metal. My improved hook is made of one piece of Steel, brass or other wire, bent in this shape one end of which is attached to the reins, or harness, and the other, or hook end to the bridle bits or other parts of the harness, one end serving as the hook and the other as a spring passing under it and pressing tightly against it so as to prevent the bits from slipping out of it.

The advantages of this hook or fastening is cheapness and perfect security. What we claim as our invention and desire to be secured by Letters Patent, is making hooks, fastening, bridle reins to the bits and other parts of the harness, by means of a bent wire hook made of one piece of metal instead of two or more pieces.
